POCKET STRUCTURE FOR GARMENTS

Filed April 15, 1929

Inventor:

Clarence W. Mastin.

John B. Thomas & Co.
Attorneys.

UNITED STATES PATENT OFFICE

CLARENCE W. MASTIN, OF SAN ANTONIO, TEXAS

POCKET STRUCTURE FOR GARMENTS

Application filed April 15, 1929. Serial No. 355,409.

My invention is an improvement in pockets for wearing apparel, and relates more especially to the construction of patch-pockets attached to the outside of the garment, as for instance to a shirt, coat, etc.

The primary object of my invention is to provide a construction of patch-pocket in the form of a multiple pocket which will have the general neat appearance of an ordinary patch-pocket with a vertical box pleat at the center and the usual flap at the upper end thereof.

A further object of my invention is to provide a patch-pocket of the general character mentioned having a pocket the opening of which is covered by the usual flap at the upper end thereof and a companion pocket with a vertical opening thereto covered by one side of the box pleat, said companion pocket providing both a safety pocket to prevent articles placed therein from accidentally falling out, and a secret pocket.

A further object of my invention is to provide in addition to the main and companion pockets a narrow pocket at one side thereof to receive a pen, pencil, or other narrow article inserted through an opening at the upper end of said pocket covered by the flap or through an opening at said connected end of the flap.

Other objects and advantages of my invention will hereinafter appear, and what I particularly claim as new and desire to protect by Letters Patent is more specifically set forth in the appended claim.

In the drawings, forming a part of this specification:—

Figure 1 is a front view of a patch-pocket constructed in accordance with my invention.

Fig. 2 is a similar view with the flap raised and the several pockets indicated in dotted lines.

Fig. 3 is a view similar to Figure 2 with parts broken away to show the formation of the pockets, and

Figs. 4 and 5 are sectional views on the lines 4—4 and 5—5 of Fig. 2.

My invention is applied to that particular type of pocket in which the material form-

ing the same is attached to the outer side of the garment 6, such as a shirt or coat, and is commonly called a patch-pocket, the upper end thereof being covered by a flap 7 secured to the material of the garment by 55 a double line of stitches 8, in the present instance said stitches terminating a short distance from the opposite ends of said flap, as shown in Fig. 1, and the material forming the two-ply flap sewed together at its opposite sides and lower end by a double line of stitches 9 at the edges thereof. By terminating the attaching stitches 8 of the flap a short distance from the sides thereof openings 10 60 are left at each side, one leading to a small 65 compartment in the pocket structure hereinafter described, the attachment of the flap to the garment being spaced from said pocket structure for access to the small compartment or pocket as well as the main pocket 70 when said flap is lifted.

In further carrying out my invention I make up the pocket structure of a lining 11 and facing material 12, the latter being preferably of the same material of which the garment is made and is provided with a box pleat 13 the meeting edges of the inner plies of which are stitched together throughout the length of the pleat and to the facing material by stitches 14 for a certain distance only 80 from the lower end of the pocket structure so that an opening 15 will be left between the upper end of said stitches 14, or tacking stitches 16 at this point, and the upper end of the pocket structure, said opening leading into a pocket 17 formed between the lining 11 and facing 12 when they are attached to the garment by the double lines of stitches 18 at the sides and lower end of said pocket structure, while a main pocket 19 is formed 90 between the lining and body of the garment. To leave an opening to the main pocket at the upper end thereof the lining and facing material only are connected by stitches 20, and to provide a narrow pocket 21 at one 95 side of the pockets 17—19—for pens, pencils, etc.—the lining 11 is stitched to the body of the garment by a line of stitches 22, with the opening 21^a into said pocket on a vertical line with the aforementioned opening 100

10 left at the attached end of the pocket flap 7. Pencil A rests in pocket 21, while pencil A' extending through opening 10^a is supported by clip a.

In providing the opening 15 which leads to the safety-pocket 17 the box pleat and facing material are not in one piece, as is usual in this general form of patch-pocket, but is made of two pieces joined together behind the face of the pleat from the bottom up to the tacking stitches 16 beyond which they are separated to the top of the pocket structure thereby leaving the opening or slit 15 at the center of the upper end of said safety-pocket, the loose edge of the section 12^a of the facing material being hemmed as usual and the meeting edges of the inner folded portions of the box pleat which is formed on the other section of the facing material sewed together throughout their length and to the lining from the bottom up to the pocket opening as hereinbefore described. The opening to the safety pocket is thereby covered by one side of the pleat, as shown in Fig. 4, and when the flap is to be buttoned on the pocket a button 23 is sewed to the box pleat and the flap provided with a button hole 24.

From the foregoing description in connection with the accompanying drawings it will be seen that I provide a patch pocket for garments in which there is a main pocket between the material of the body of the garment and lining of the pocket structure to which access is had immediately below the flap, and that a safety pocket approximating the size of said main pocket is provided between the lining and facing material having the box pleat, with a narrow pencil pocket at one side of the aforesaid pockets opening out below the attached end of the flap as well as through the inner attached end of the flap, the particular construction of both the pocket structure and flap giving the general outer appearance of an ordinary patch pocket, whereby the safety pocket is also of the nature of a secret pocket, as the opening thereto is covered by the box pleat. In using the small pocket the upper end of the article, as a pencil, if of such length as to extend through the opening in the attached end of the flap will not interfere with the opening of the flap to gain access to the main pocket (see Figs. 1 and 2), and of course can be removed without lifting the flap, while access to the safety pocket is reached beneath the upper part of one side of the box pleat, and this pocket opening being at the upper part of the pocket at the center thereof and shielded by the box pleat will safely retain articles within said pocket.

Obviously the opening to the safety pocket may be provided should the pocket facing and box pleat be formed from one piece of material, in which instance the slit for the

opening to said pocket would be formed by cutting the material for the desired distance from the top thereof at one side of the connected inner folds of said box pleat, but the construction shown and described is preferable for economy of construction. Likewise other modifications may be resorted to in carrying out my invention, within the spirit and scope of the appended claim.

I claim:

A patch pocket for garments comprising a lining and facing material attached to each other around the edges thereof and to the garment at the edges of the sides and lower end to provide an inner or main pocket opening out at its upper end and an auxiliary pocket between the lining and facing material, a vertical box pleat formed on the outer side of the facing at the center thereof, and a slit through the facing material behind the center of the box pleat leading into the upper part of the auxiliary pocket between the facing and lining, the box pleat being sewed to the facing material at one side of the slit and to both sides of said facing material from the slit to the bottom of the auxiliary pocket.
